The ornamental design for a multimodal cleaning brush, as shown and described.

DESCRIPTION

FIG. 1 is a perspective view of a multimodal cleaning brush;

FIG. 2 is a bottom view thereof;

FIG. 3 is a right-hand side view thereof, the left-hand side being a mirror image;

FIG. 4 is a front view thereof; and,

FIG. 5 is a rear view thereof.

The broken line showing portions of the multimodal cleaning brush illustrates environment of the claimed design and forms no part thereof.
